UNITED STATES PATENT OFFICE.

BENJAMIN JOACHIM, OF NEWARK, NEW JERSEY, AND BENJAMIN DAVIDSON, OF LOS ANGELES, CALIFORNIA.

MEANS FOR ATTACHING COLLARS AND OTHER NECKWEAR TO SHIRTS.

1,139,293.

Specification of Letters Patent. Patented May 11, 1915.

Application filed April 1, 1913. Serial No. 758,120.

To all whom it may concern:

Be it known that we, BENJAMIN JOACHIM, a resident of Newark, in the county of Essex and State of New Jersey, and BENJAMIN DAVIDSON, a resident of Los Angeles, in the county of Los Angeles and State of California, both citizens of the United States, have invented a new and Improved Means 5 for Attaching Collars and other Neckwear to Shirts, of which the following is a full, clear, and exact description.

This invention has special reference to means for attaching collars and other neckwear to shirts, and broadly speaking, the invention constitutes a tangible element carried by the neck band of a shirt and an intangible element carried by the collar or neckwear for convenient attachment and removal of the collar at the back of the neck band, thus providing space for the free sliding of the tie, as well as obviating the use of buttons.

In carrying out our invention, it is our aim to provide the neck band of a shirt with a tongue extending downwardly to form a substantially hook-like member, and to provide the collar with a pocket, or to provide a plurality of such tongues and pockets, for attaching the collar and not only permitting its convenient attachment and removal, but also causing a better fit and permitting collars and shirts to be manufactured with but a slight modification and laundried in the usual manner.

With the above and other objects in view, the invention resides more particularly in the peculiar combinations and arrangements of parts which will be illustrated as a preferred embodiment in the accompanying drawings and described in the specification.

Reference is to be had to the accompanying drawings forming a part of this specification, in which similar characters of reference indicate corresponding parts in all the views, and in which—

Figure 1 is a vertical sectional view of a collar and a fragmentary portion of a shirt, with the collar held on the neck band; Fig. 2 is a perspective view of a fragmentary portion of a shirt and its neck band with its collar-engaging member; Fig. 3 is a perspective view of a fragmentary portion of a collar having a pocket; Fig. 4 is a similar view of a collar with a modified form of pocket; Fig. 5 is a rear elevation of a shirt

portion and its neck band having a plurality of hook-like attaching members; and Fig. 6 is a similar view of a collar, with a plurality of pockets.

In the illustrated embodiment of the invention shown in Figs. 1, 2 and 3, the numeral 10 designates a collar of any preferred type and any number of plies, although we have illustrated the same as being made of three-ply. A fragmentary portion 11 of 60 a shirt is also shown, and the neck band 12 is provided with a depending tongue or hook-like member 13, the same being formed with, attached to or otherwise carried by the neck band, and preferably depending from the 65 top edge of the latter to a point near its lower edge. The free extremity of the tongue is also preferably rounded as shown.

The tongue 13, which forms with the neck band a substantially hook-like engaging 70 member, takes the place of an ordinary collar button and is of such material as to be laundried with the shirt. In order to provide a collar to be engaged by the tongue or hook-like member, the inner plies of the collar 75 are cut longitudinally, as shown at 14, to produce a relatively elongated pocket 15 with the outer plies, and such pocket is adapted to be engaged by the tongue in the manner shown in Fig. 1 of the drawings. 80

Owing to the fact that the pocket forms an inclosure for the tongue, it will be seen that any tendency of the collar to ride upwardly will be prevented by the forcive engagement of the opposed faces of the tongue 85 with the inner faces of the plies forming the pocket, and since the free end of the tongue is preferably located at a point adjacent the base of the neck band of the shirt, only a very limited downward displacement of the 90 collar with respect to the neck band will be permitted, and in this manner the collar will be prevented from being accidentally displaced with respect to the band or the tongue 95 with respect to the pocket. 100

In Fig. 4 of the drawings a modified form of pocket is illustrated, the same being designated by the numeral 16 as a section forming a relatively restricted slot or opening in the collar so as to conform to the shape of 105 the tongue or hook-like engaging member carried by the band, and in this way prevent movement of the collar with respect to the band if desired.

In Figs. 5 and 6 of the drawings a modi- 110

fied form of attaching means is illustrated, and the neck band shown in Fig. 5 is provided with a plurality of depending tongues 18, which in this case are shown as extending 5 from a point spaced below the top edge of the neck band but terminating at their free ends near the bottom edge or base of the neck band. As shown, there is provided a central tongue at the back portion of the 10 neck band and another tongue on either side of the central tongue. In Fig. 6 a collar 19 is shown as adapted for use with the attaching means illustrated in Fig. 5 of the drawings, and in this form of the invention the 15 collar is provided with a plurality of pockets 20 which may take either of the forms above described. It is, of course, understood that these pockets are equi-distantly spaced with respect to the relation or spacing 20 of the tongues 18 so that the parts may be readily engaged in attaching the collar. Thus it will be seen that we have obviated the necessity of using buttons for attaching collars to neck bands or for securing other 25 neckwear to shirts, especially at the back portion, and thus we have obviated the objections usually resulting from the using of buttons. The shirt and collar may be laundered in the usual manner and the elements 30 carried thereby form a permanent, wear-resisting and reliable attaching means.

Having thus described our invention, what we claim as new and desire to secure by Letters Patent is:

35 1. The combination with a neck band having a tongue; of a collar having a pocket located between the plies of the collar and engageable by said tongue, said pocket having an open end and closed sides at the entrance opening thereof and a bottom for engagement by the end of the tongue, whereby displacement of the tongue laterally is prevented.

2. The combination with the neck portion 40 of an article of apparel having a plurality of tongues disposed centrally and at the

sides thereof, said tongues depending from a point below the upper edge of said neck portion and spaced therefrom to produce engaging members; of a second article of apparel such as a collar, having pockets engaged by said members, said pockets having closed lower ends and open upper ends adapted to receive the engaging members produced by said tongues.

3. The combination with the neck band of a shirt comprising a plurality of plies of material and having the usual buttonholes at the ends thereof and a plurality of tongues stamped from certain plies of the material, said tongues being located centrally of the length of the band at the back thereof when the band is in position and at spaced points at either side of the central tongue and inwardly of the buttonholes; of a collar also comprising a plurality of plies and having buttonholes near its ends and pockets located between certain plies thereof in similar relation to the disposition of the tongues in the band and adapted to be engaged by said tongues to secure the collar to the band and prevent upward displacement thereof relative thereto, said tongues when engaged in the pockets being hidden from view.

In testimony whereof I, BENJAMIN JOACHIM, have signed my name to this specification in the presence of two subscribing witnesses.

BENJAMIN JOACHIM.
